ARMORED ELECTRIC CONDUCTOR

Application filed November 27, 1928. Serial No. 322,137.

This invention relates to what are known as armored electric conductors in which the insulated wire or wires are contained within an outer metallic casing formed by spirally winding a metallic strip and fashioning such strip to interlock the separate windings to permit the flexure of said casing; and the object of the invention is to provide the insulated conductor or conductors with protective coverings, sheaths or jackets, one consisting of a braided body and the other of a wrapping spirally wound upon the braided jacket with adjacent edges of the wrapping overlapped to interlock one wrapping with the other to provide a continuous enclosure for the conductor regardless of the degree of flexure to which the same is subjected; a further object being to provide means for reinforcing and shielding the conductor or conductors at the cut or severed end of the armored outer casing to prevent the rupturing of the protective casings of the conductor or conductors and to further prevent short circuiting between the conductor and casing; a still further object being to provide a reinforcing and shielding means in the forming of a body and insulating material adapted to be positioned between the outer armored casing and the spirally wrapped casing or jacket on the conductor or conductors, said insulated body having a pronged end or ends facilitating the placement thereof in the position stated, and being adapted to flex or expand the free end of the outer armored casing in the operation of placing the same in position, which in turn firmly supports the conductor or conductors within the outer casing at the free end thereof; and with these and other objects in view, the invention consists in an armored conductor of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of one form of conductor which I employ with part of the construction broken away.

Fig. 2 is a section on the line 2—2 of Fig. 1.

Fig. 3 is a longitudinal, sectional view of the structure shown in Fig. 1 with one of the coverings torn off. 55

Fig. 4 is a view similar to Fig. 1 showing a modified form of covering.

Fig. 5 is a view similar to Fig. 3 showing another form of covering. 60

Fig. 6 is a detail view of one of the reinforcing and insulating shields which I employ.

Fig. 7 is a perspective view of the shield shown in Fig. 6 formed for use. 65

Fig. 8 is a view similar to Fig. 7 showing a slight modification.

Fig. 9 is a plan view of a blank from which a modified form of shield is made. 70

Fig. 10 is a view similar to Fig. 2 showing a modified form of conductor and illustrating the use of the blank shown in Fig. 9.

Fig. 11 is a view similar to Fig. 10 showing another form of conductor and also illustrating the blank shown in Fig. 9; and, 75

Fig. 12 is a view similar to Fig. 5 showing another modification.

In Figs. 1 to 5 inclusive, I have shown an armored conductor comprising an outer armored casing 15 in which is contained two conductor strands or wires 17 and 18 first enclosed in a rubber casing or jacket 17^a and 18^a and then in a braided casing or jacket 17^b and 18^b. The cross section of the conductors is seen in Fig. 2 of the drawing. 80

The armored casing may be produced in any desired manner and of any suitable construction, the one shown being merely to illustrate one application of the invention. This casing is formed as is customary from a metallic strip which is fashioned to a predetermined cross sectional form and spirally wound in overlapped interlocking relation. 90

In Figs. 1, 2 and 3 of the drawing, the conductors 17 and 18 with the two coverings or jackets 17^a—18^a and 17^b—18^b thereon are enclosed in another protective casing or jacket 19 which consists of a comparatively wide strip spirally wrapped around both conductors. 95

tors, the separate conductors being arranged in a twisted or spiral state, and one half of the strip 19^a from which the casing 19 is formed overlies the adjacent half of the previously wound portion of the strip so as to permit the flexure of the conductor without rupturing the casing 19 or without parting or separating the separate coils or windings of the strip.

10 Instead of winding a single and comparatively wide strip upon the conductors to form the casing 19, I may wind a plurality of comparatively narrow strips 20^a to form a casing or protector covering 20 such as seen in Fig.

15 4. Each strip is preferably wound to overly a portion of an adjacent strip as clearly seen in said figure. The strip shown in Figs. 1 and 2 in forming the casings 19 and 20 are preferably composed of paper or a prepared paper of single or multiple thickness. Further, these casings or strips may be treated to render the same moisture and fire proof. This is also true of the braided coverings 17^b and 18^b.

25 In Fig. 5 of the drawing, I have shown another modification wherein the two conductors with the braided casings thereon are contained in an outer braided casing or jacket 21 encircling both of the conductors and arranged between the same and the outer armored casing 15. The casing 21 may also be treated to render the same fire and moisture proof.

In Figs. 10 and 11 of the drawing, I have shown other modifications in the general construction of the armored conductor, and in Fig. 10, I have shown three conductors 22, 23 and 24 arranged within the outer armored casing 15, each of the conductors 23—24 being of the same construction as the conductors 17 and 18 and being enclosed in a single protector casing or jacket 25 which may be of either of the forms shown in Figs. 1, 4 and 5 of the drawing.

45 In Fig. 11, I have shown a single conductor 26 arranged within the armored casing 5, and this conductor is also of the same construction as either one of the conductors 17 and 18 and is enclosed in a protector casing or jacket 27 similar to either of those shown in Figs. 1, 4 and 5 of the drawing.

In the use of armored conductors of the class under consideration, it is customary to cut off predetermined lengths thereof in coupling the conductor strands 17 and 18 with outlet boxes, electric fixtures, fittings or the like. In this practice, it is also customary to cut by means of a hack saw or other tool, a diagonal cut 28, across one of the coils of the outer armored casing 15 to sever the remaining end portion of such casing from the main body thereof. This practice leaves a pointed and ragged projecting corner portion 29, note Figs. 1 and 4 of the drawing.

65 This projecting sharp and ragged corner 29

is objectionable in that it has been experienced in the use of conductors of this class that the insulated strands 17 and 18 have been pierced to form a short circuit through the armored outer casing 15 which is usually grounded, and this is experienced especially when part of the protective coverings or casings of the conductors proper are ruptured by the saw or other tool in severing the outer armor.

To obviate this, I provide a guard or shield member 30 preferably composed of insulating material which serves to reinforce and strengthen the armored conductor at the end of the armored casing 15 thereof and to insulate the conductor strands 17 and 18 from the grounded casing.

The shield 30 which is employed in the construction shown in Figs. 1 to 5 inclusive and which is shown in detail in Figs. 6, 7 and 8 of the drawing consists of a cross-head body portion 31 having extending from one side thereof two prong members 32 which when the crosshead 31 is folded to form a cylindrical or substantially ring-like body as seen in Fig. 7 of the drawing, disposes the prongs 32 in opposite relation.

In the use of the shields 30, the prongs 32 are passed into the armored casing 15 through the recesses or chambers 33 formed at the opposite sides of the wrapped conductors by virtue of the twisting thereof, these recesses being shown clearly in Fig. 2 of the drawing. By forcing the shield 30 inwardly by hand or by the use of a suitable tool, the ring-like crosshead 31 will come into contact with the inner wall of the end portion of the casing 15, and serve to slightly extend the same by virtue of the outward internal pressure until the entire ring-like crosshead 31 has been arranged within the end of said casing, it being preferred that the ends of the crosshead or ring body 31 overlap to a slight degree. When in position, the shield will be located between the outer protector casing 19 and the armored casing 15 as clearly seen in Figs. 1 and 3 of the drawing, and when in position, the free end of the casing 19 may be unravelled and torn off adjacent the outer edge of the shield 30 as seen at 34 in Fig. 3 of the drawing, thus allowing the separate strands 17 and 18 to be freely flexed and stripped off of their casings 17^a, 18^a, 17^b, 18^b to expose the wires to permit their coupling with suitable terminals.

In the above operation of inserting the shield or guard 30, the expansion of the free end portion of the casing 15 is represented by the separation of the free edge of the strip with respect to a saw cut in the adjacent coil of the strip as will be noted at x, in Figs. 1 and 4 of the drawing. It will be understood at this time that the guard 30 will be held in position frictionally or under the tension of the expanded coil or winding of

the strip from which the casing 15 is formed. If desired, an additional precaution or safeguard may be added to the shield structure in the form of an outwardly and backwardly extending flange portion 34, note Fig. 8 of the drawing, which flange portion is severed at circumferentially spaced intervals to form separate flange members 34* which will overlie the free edge of the last winding of the strip from which the casing 15 is formed and will overlie the corner portion 29 thereof as will be apparent.

In Fig. 9 of the drawing, I have shown a modified form of shield or guard 35 comprising a crosshead portion 36 which is adapted to be folded or rolled into a ring or loop. At one side of the crosshead are three extending prongs 37. If desired, this form of shield or guard may be constructed with a flange such as that illustrated in Fig. 8. The type of shield shown in Fig. 9 of the drawing is designed for use in connection with conductors of the class illustrated in Figs. 10 and 11 of the drawing, and especially in Fig. 10, in which figure, the three conductors 22, 23 and 24 wrapped in the protector casing or jacket 25 will present within the armored casing 15, three spaced recesses 38 in which the prongs 37 of the shield are adapted to pass in the same manner as placing the prongs 32 in the oppositely disposed recesses 33 as in the construction shown in Fig. 2.

While the shield 35 is also preferably used in the single strand conductor as seen in Fig. 11 to insure the expansion of the free end of the armored casing 15, it will be apparent that the shield shown in Fig. 7 or in fact a shield such as shown in Fig. 12 may be used, it being further understood that the shield 39 which is shown in Fig. 12 may be employed in connection with either of the conductors shown in Figs. 2 and 10 of the drawings. The shield 39 is in the form of a pronged body which is V-shaped or wedge-shaped in form, having a single tapered prong 40 and the crosshead is restricted in transverse dimensions so as to only partially encircle the conductor or conductors contained within the protector casing employ, such for example as the casings 19, 20, 21, 25 and 27.

With this type of shield, the same is preferably positioned at the cut portion of the armored casing 15 or where the cut 28 is formed therein as well as where the ragged 55 and pointed edge 29 is located, the shield being preferably stamped out to form a bead or rib 41 which will cooperate with the cut end of the outer casing to prevent shifting or displacement of the shield, or to aid in this respect, in addition to the frictional or tensional engagement of the shield. It will also be apparent that the prongs of the other shields shown may be correspondingly formed. The outer or crosshead end of the 65 shield 39 is also preferably provided with a

backwardly turned flange 42 adapted to overlie the free edge of the armored casing 15.

It will be understood that after the shield has been placed in position, the unravelling and severing of the protector casings 19, 20 and 21 as well as the casings 25 and 27 is facilitated, in that the shields are held firmly in position and form a stop to check the further unravelling or severing of the protector covering. It will also be noted that I maintain the full protection of the conductor strands within the free end portion of the armored casing thus affording the greatest possible safety and protection to said conductor strands.

It is also preferred that the guards or shields 30, 36 and 39 be preferably treated with a suitable compound to render them fire and moisture proof, and also to facilitate the placement of said shields in position, it being preferred that a wax-like or greasy compound be employed, and in some instances, these shields may be treated with a suitable wax or paraffin to facilitate this result. It will also be understood that my invention is not necessarily limited to any particular form or contour of the guard or shield members employed, nor to the specific armored conductors herein shown and described, and various other changes in and modifications of the construction set out may be made within the scope of the appended claims without departing from the spirit of my invention or sacrificing its advantages.

Having fully described my invention, what I claim as new and desire to secure by Letters Patent, is:—

1. A conductor of the class described comprising an insulated conductor strand, an outer spirally wound protector casing of insulating material on said insulated strand, an armored casing enclosing said last named casing, and a shield of insulating material adapted to be forced into position between one end portion of the armored casing and said outer protector casing.

2. A conductor of the class described comprising an insulated conductor strand, an outer spirally wound protector casing of insulating material on said insulated strand, an armored casing enclosing said last named casing, a shield of insulating material adapted to be forced into position between one end portion of the armored casing and said outer protector casing, and said shield comprising a pronged body adapted to be arranged beneath the cut portion of the armored casing.

3. A conductor of the class described comprising an insulated conductor strand, an outer spirally wound protector casing of insulating material on said insulated strand, an armored casing enclosing said last named casing, a shield of insulating material adapted to be forced into position between one end portion of the armored casing and said outer

- protector casing, said shield comprising a pronged body adapted to be arranged beneath the cut portion of the armored casing and being adapted to expand the free end portion of the armored casing, and part of said shield encircling the protector casing at the free end portion of the armored casing. 5 70
4. In an armored conductor of the class described, a protector shield composed of insulating material adapted to be wedged between the armored casing of the conductor and the outer insulating body thereof at the end portion of said armored casing, said shield comprising a split and tubular body having a pronged end portion. 10 75
5. In an armored conductor of the class described, a protector shield composed of insulating material and adapted to be wedged between the armored casing of the conductor and the outer insulating body thereof at the end portion of said casing, said shield comprising a split tubular body having a pronged end portion, said body being treated with a compound having greasy properties. 20 80
6. In an armored conductor comprising an outer flexible metallic casing in which are arranged insulated conductor strands contained in a protector casing in such fashion as to form spaced recesses within said casing and around the conductor, an insulator shield in the form of a split tubular body having prong elements at one end thereof insertable into said recesses and to position the split tubular portion thereof at the free end of the armored casing to guard and insulate said end of the casing from the conductor strands contained therein. 30 85
7. A conductor of the class described comprising an insulated conductor strand, a spirally wound protector casing of insulating material on said insulated strand, an outer armored casing enclosing said last named casing, a shield of insulating material adapted to be forced into position between one end portion of the outer armored casing and said protector casing, and said shield serving to check and stop the unravelling of the spirally wound protector casing and facilitating the severing of said strand at the outer end of said shield. 40 90
8. A shield for use in conjunction with armored conductors of the class described comprising a pronged body of relatively rigid insulating material. 50 95
9. A shield for use in conjunction with armored conductors of the class described comprising a pronged body of relatively rigid material having insulating properties. 55 100
10. A shield for use in conjunction with armored conductors of the class described comprising a pronged body of relatively rigid material having insulating properties, and said body being treated with a compound having greasy properties. 60 105
11. A shield for use in conjunction with armored conductors of the class described comprising a pronged body of relatively rigid insulating material, said body having a split tubular collar at one end, and said collar being provided with an outwardly and backwardly turned flange. 65 110
12. A shield for use in conjunction with armored conductors of the class described comprising a pronged body of relatively rigid insulating material, and the prong portion of said body being ribbed. 70 115
13. A shield for use in conjunction with armored conductors of the class described comprising a split tubular body of relatively rigid insulating material, and one end portion of said body having spaced prongs. 75 120
14. In an armored conductor of the class described, a protector shield composed of insulating material adapted to be wedged between the armored casing of the conductor and the outer insulating body thereof at the end portion of said armored casing, said shield comprising a split and tubular body having a pronged end portion, and the other end portion of said body having an outwardly projecting annular flange. 80 125
15. In an armored conductor comprising an outer flexible metallic casing in which are arranged insulated conductor strands contained in a protector casing in such fashion as to form spaced recesses within said casing and around the conductor, an insulator shield in the form of a split tubular body having prong elements at one end thereof insertable into said recesses and to position the split tubular portion thereof at the free end of the armored casing to guard and insulate said end of the casing from the conductor strands contained therein, said shield including an outwardly and backwardly turned flange adapted to overly the free edge of the outer casing. 85 130
16. In combination with an armored cable having a cable armor and an insulated conductor container within and having an end portion projecting outwardly from an end of said cable armor, a shield of insulating material for protecting the projecting end portion of said insulated conductor from the abrasive action of the end of said cable armor, said shield being interposed between the insulation of said conductor and the inner surface of said cable armor, and having a portion overlying the end of said cable armor and locking means formed on said shield for engaging said cable armor to retain said shield in desired position. 90 135
17. In combination with an armored cable having a cable armor and an insulated conductor contained within and having an end portion projecting outwardly from an end of said cable armor, a shield of insulating material for protecting the projecting end portion of said insulated conductor from the abrasive action of the end of said cable armor. 95 140

- armor, said shield being interposed between the insulation of said conductor and the inner surface of said cable armor, and having a portion overlying the end of said cable
- 5 armor and locking means formed on said shield for engaging said cable armor to retain said shield in desired position, said locking means consisting of a radially extending protuberance struck outwardly from the body of said shield.
- 10 18. An insulator shield for conductors of the class specified comprising a split tubular body of insulating material, the walls of the split portion being beveled and curved at one end of said body to form a prong end portion.
- 15 19. An insulator shield for conductors of the class specified comprising a split tubular body of insulating material, the walls of the split portion being beveled and curved at one end of said body to form a prong end portion and the other end of said body having a radially and outwardly projecting member.
- 20 20. In combination with an armored cable having a cable armor, insulated conductors extending side by side within said cable armor and having end portions projecting outwardly from an end of said cable armor,
- 25 and additional insulation wrapped around said conductors and fitting snugly within said cable armor, a shield having a converging inner end portion interposed between said additional insulation and said cable armor, said converging end portion facilitating the ready insertion of said shield under said cable armor, said shield having a marginal flange on its outer end portion overlying the end of said cable armor.
- 30 In testimony that I claim the foregoing as my invention I have signed my name this
- 35 24th day of November, 1928.
- 40 EDWIN J. SCHNEIDER.
